Primary Examiner — Ryan Reis*(74) Attorney, Agent, or Firm* — Harness, Dickey & Pierce, P.L.C.(57) **ABSTRACT**

A sprayer for spraying a fluid can include a sprayer body, a fluid reservoir, a trigger assembly, a flow adjustment mechanism and an air horn assembly. The sprayer body can include a nozzle assembly that defines a fluid outlet and includes a needle arranged within a fluid conduit. The fluid reservoir can be coupled to the sprayer body and be in communication with the fluid outlet and fluid conduit. The trigger assembly can be coupled to the nozzle assembly and be configured to move the needle as the trigger assembly is depressed. The flow adjustment mechanism can be configured to adjust a flow rate of the sprayer. The air horn can include at least one air horn projection that limits rotation of the air horn between a first position corresponding to a vertical spray pattern and a second position corresponding to a horizontal spray pattern.

PAINT SPRAYER

**CROSS-REFERENCE TO RELATED
APPLICATIONS**

This application claims the benefit of U.S. Provisional Application No. 61/261,953, filed on Nov. 17, 2009. The entire disclosure of the above application is incorporated herein by reference.

FIELD

The present disclosure relates to a sprayer for spraying fluids including paints and stains.

BACKGROUND

Paint sprayers are well-known in the art. For example, U.S. Pat. No. 7,360,720 discloses a spray gun for spraying paints, lacquers or similar media. This and other conventional spray guns can have a number of drawbacks. For example, conventional spray guns often lack an adequate indication to a user of the flow rate of the sprayer. Further, it is often difficult to refill the reservoir and adjust the spray pattern of conventional paint sprayers.

I would be desirable to provide a sprayer that includes an indication of the flow rate of the sprayer to the user and also simplifies the refilling of the sprayer and adjustment of the spray pattern.

SUMMARY

This section provides a general summary of the disclosure, and is not a comprehensive disclosure of its full scope or all of its features.

In some embodiments of the present disclosure, a sprayer for spraying a fluid can include a sprayer body, a fluid reservoir, a trigger assembly, a flow adjustment mechanism and an air horn assembly. The sprayer body can include a handle portion and a nozzle portion. The nozzle portion can include a nozzle assembly that defines a fluid outlet and that includes a fluid conduit and a needle arranged within the fluid conduit and extending in an axial direction. The needle can be movable to a plurality of positions between a closed position and a fully opened position, the needle closing the fluid outlet in the closed position and fully opening the fluid outlet in the fully opened position. The fluid reservoir can be coupled to the sprayer body and be in communication with the fluid outlet and fluid conduit. The trigger assembly can be coupled to the nozzle assembly and be configured to move the needle as the trigger assembly is depressed. The flow adjustment mechanism can be coupled to the trigger assembly and be configured to adjust a flow rate of the sprayer by limiting movement of the trigger assembly and the needle. The air horn assembly can include a collar removably coupled to the nozzle portion and a rotatable air horn arranged between the collar and nozzle portion. The air horn assembly can be configured to permit rotation of the air horn to a plurality of positions. The air horn can include at least one air horn projection that limits rotation of the air horn between a first position corresponding to a vertical spray pattern and a second position corresponding to a horizontal spray pattern.

In other embodiments, a sprayer for spraying a fluid can include a sprayer body, a fluid reservoir, a trigger assembly, a flow adjustment mechanism and an air horn assembly. The sprayer body can include a handle portion and a nozzle portion. The nozzle portion can include a nozzle assembly that

2

defines a fluid outlet and that includes a fluid conduit and a needle arranged within the fluid conduit and extending in an axial direction. The needle can be movable to a plurality of positions between a closed position and a fully opened position, the needle closing the fluid outlet in the closed position and fully opening the fluid outlet in the fully opened position. The fluid reservoir can be coupled to the sprayer body and be in communication with the fluid outlet and fluid conduit. The trigger assembly can be coupled to the nozzle assembly and be configured to move the needle as the trigger assembly is depressed. The flow adjustment mechanism can be coupled to the trigger assembly and be configured to adjust a flow rate of the sprayer by limiting movement of the trigger assembly and the needle. The air horn assembly can include a collar removably coupled to the nozzle portion and a rotatable air horn arranged between the collar and nozzle portion. The air horn assembly can be configured to permit rotation of the air horn to a plurality of positions. The nozzle portion can include a ridge member that acts as a mechanical stop for the collar. The ridge member and collar can be configured to permit rotation of the air horn without loosening the collar from a fully tightened position in which the collar is in contact with the ridge member.

In various other embodiments, a sprayer for spraying a fluid can include a sprayer body, a fluid reservoir, a trigger assembly, a flow adjustment mechanism and an air horn assembly. The sprayer body can include a handle portion and a nozzle portion. The nozzle portion can include a nozzle assembly that defines a fluid outlet and that includes a fluid conduit and a needle arranged within the fluid conduit and extending in an axial direction. The needle can be movable to a plurality of positions between a closed position and a fully opened position, the needle closing the fluid outlet in the closed position and fully opening the fluid outlet in the fully opened position. The fluid reservoir can be coupled to the sprayer body and be in communication with the fluid outlet and fluid conduit. The trigger assembly can be coupled to the nozzle assembly and be configured to move the needle as the trigger assembly is depressed. The flow adjustment mechanism can be coupled to the trigger assembly and be configured to adjust a flow rate of the sprayer. The air horn assembly can include a collar removably coupled to the nozzle portion, an air diffuser coupled to the nozzle portion and a rotatable air horn arranged between the collar and air diffuser. The air horn assembly can be configured to permit rotation of the air horn to a plurality of positions. The nozzle portion can include a ridge member that acts as a mechanical stop for the collar. The ridge member and collar can be configured to permit rotation of the air horn without loosening the collar from a fully tightened position in which the collar is in contact with the ridge member. The air horn can include at least one air horn projection and the air diffuser can include at least one stop surface that interacts with the at least one air horn projection to limit rotation of the air horn between a first position corresponding to a vertical spray pattern and a second position corresponding to a horizontal spray pattern.

Further areas of applicability will become apparent from the description provided herein. The description and specific examples in this summary are intended for purposes of illustration only and are not intended to limit the scope of the present disclosure.

DRAWINGS

The drawings described herein are for illustrative purposes only of selected embodiments and not all possible implementations, and are not intended to limit the scope of the present disclosure.

FIG. 1 is a perspective view of a first exemplary sprayer constructed in accordance with the teachings of the present disclosure;

FIG. 2 is a section view of the sprayer of FIG. 1;

FIG. 3 is a perspective view of a second exemplary sprayer constructed in accordance with the teachings of the present disclosure;

FIG. 4 is a section view of the sprayer of FIG. 3;

FIG. 5 is a partially exploded perspective view of a portion of the sprayer of FIG. 3;

FIG. 6 is a perspective view of a portion of the sprayer of FIG. 3;

FIG. 7 is a perspective view of a flow adjustment mechanism of the sprayer of FIG. 3;

FIG. 8 is a top elevation view of the sprayer of FIG. 3 illustrating a portion of the flow adjustment mechanism;

FIG. 9 is a perspective view of an exemplary trigger plunger constructed in accordance with the teachings of the present disclosure;

FIG. 10 is a perspective view of a portion of the sprayer of FIG. 1 illustrating an exemplary flow rate adjustment mechanism constructed in accordance with the teachings of the present disclosure in a first condition;

FIG. 11 is a perspective view of a portion of the sprayer of FIG. 1 illustrating the exemplary flow rate adjustment mechanism of FIG. 10 in a second condition;

FIG. 12 is a perspective view of an exemplary reservoir constructed in accordance with the teachings of the present disclosure;

FIG. 13 is a section view of the reservoir of FIG. 12;

FIG. 14 is a section view of a portion of the sprayer of FIGS. 1 and 3 with the reservoir of FIG. 12 attached thereto illustrating an exemplary check valve assembly constructed in accordance with the teachings of the present disclosure;

FIG. 15 is a partially exploded perspective view of a portion of the sprayer of FIG. 1 illustrating an exemplary air horn assembly constructed in accordance with the teachings of the present disclosure;

FIGS. 16A and 16B are perspective views of a portion of the sprayer of FIG. 1 illustrating a portion of the exemplary air horn assembly of FIG. 15; and

FIG. 17 is a section view of a portion of the sprayer of FIG. 1 illustrating a portion of the exemplary air horn assembly of FIG. 15.

Corresponding reference numerals indicate corresponding parts throughout the several views of the drawings.

DETAILED DESCRIPTION

Example embodiments will now be described more fully with reference to the accompanying drawings.

With reference to FIG. 1 of the drawings, a first sprayer constructed in accordance with the teachings of the present disclosure is generally indicated by reference numeral 10. The sprayer 10 can include a sprayer body 12 and a reservoir 14 that can be removably coupled to the sprayer body 12. In the particular example illustrated in FIG. 1, the sprayer 10 is a handheld high volume low pressure (HVLP) sprayer for spraying fluids, e.g., paints and stains. One skilled in the art will appreciate that the teachings of the present disclosure can apply to other types of sprayers, such as but not limited to solenoid-type sprayers and floor based, HVLP sprayers.

With reference to FIGS. 1 and 2, the sprayer body 12 can comprise a handle portion 20 and a nozzle portion 30. The handle portion 20 can include a graspable member 21 that is shaped to correspond to a user's hand. The graspable member 21 can include a cushion 22 made of rubber or similar mate-

rial to enhance the comfort and gripability of the graspable member 21. A power supply 50 can be arranged within the handle portion 20. Power supply 50 can comprise a rechargeable battery pack, removable or otherwise, or similar source of portable power. Alternatively, power supply 50 can include an AC/DC converter or similar circuit to provide operating power to the electrical components of sprayer 10 (such as motor and fan assembly 40) from a source of AC power. For example, power cord 52 can be electrically connected and provide AC power to power supply 50. Power cord 52 can include a plug (not shown) that can be plugged into a standard household outlet or other source of AC power, as is well known in the art. A switch 54 can be electrically connected to the power supply 50 in order to selectively provide operating power to the sprayer 10.

The handle portion 20 can also define an air supply chamber 23. Air supply chamber 23 can provide pressurized air to the nozzle portion 30 in order to operate sprayer 10, as described more fully below. Air supply chamber 23 can be arranged between a housing cap 46 and a handle air outlet 25. As shown in the example illustrated in FIG. 2, a motor and fan assembly 40 can be arranged within the air supply chamber 23. Motor and fan assembly 40 can include an electric motor 42 coupled to and powering a fan 44. Fan 44 can generate an air flow from outside of sprayer 10, through aperture(s) 46a defined in housing cap 46 and into air supply chamber 23. An air filter 48 can be arranged within this air flow path to filter the air to remove any foreign objects that could damage sprayer 10. Motor and fan assembly 40 and handle air outlet 25 can be configured such that the air within air supply chamber (and exiting handle air outlet 25) is at a pressure that is relatively constant during operation of the sprayer 10.

Nozzle portion 30 can be sealingly engaged with the handle portion 20 such that pressurized air exiting the handle air outlet 25 can be received within a pressurized air passageway 32 defined by the nozzle portion 30. Pressurized air passageway 32 can be a cylindrical aperture extending from a first end 30a coupled to the handle portion 20 and a second end 30b. An air horn assembly 90 can be coupled to the second end 30b of pressurized air passageway 32. During operation of the sprayer 10, pressurized air can travel from air supply chamber 23, through handle air outlet 25 and into pressurized air passageway 32, and then exit pressurized air passageway 32 through one or more air horn apertures 91 defined by the air horn assembly 90. The configuration of the one or more air horn apertures 91 can determine the spray pattern of sprayer 10.

In some embodiments, nozzle portion 30 can be removably coupled to handle portion 20. For example, the first end 30a of nozzle portion 30 can be received within an aperture 26 defined by handle portion 20. Aperture 26 can be sized to complement first end 30a such that handle portion 20 and nozzle portion 30 are frictionally engaged. In some embodiments, handle portion 20 and nozzle portion 30 can be threadably coupled by including complementary threads on each of handle portion 20 and nozzle portion 30. Handle portion 20 and nozzle portion 30 can also be coupled with a quick-disconnect mechanism 27, as shown in FIG. 2. Quick-disconnect mechanism 27 can include a push-button 27a coupled to a catch 27b that engages with a groove 28 formed in the nozzle portion 30. A biasing member, such as spring 27c, can be included to bias the quick-disconnect mechanism 27 to the locked position. A user can depress push button 27a to move the catch 27b to an unlocked position, which allows the nozzle portion 30 to be removed from handle portion 20. One or more seals 29 can be included to seal the interface between

handle portion 20 and nozzle portion 30 such that pressurized air does not escape through this interface.

A nozzle assembly 33 can be arranged within the nozzle portion 30 and include a nozzle 34, a fluid conduit 35 and a needle 36 arranged within the fluid conduit 35. The nozzle 34 can define a fluid outlet 37 in communication with the fluid conduit 35. The needle 36 can be movable to a plurality of positions between a closed position (shown in FIG. 2) in which the needle 36 closes the fluid outlet 37, and a fully opened position in which the needle 36 is retracted to fully open the fluid outlet 37. Based on the position of the needle 36, the size of the nozzle aperture 37a (see FIG. 17) defined between the needle 36 and fluid outlet 37 can be variable, thus varying the amount of fluid that exits fluid outlet 37. A biasing member, e.g., spring 38, can bias the needle 36 to the closed position. Pressurized fluid can be provided to the fluid conduit 35 such that fluid will exit the fluid conduit 35 through fluid outlet 37 when the needle 36 opens the fluid outlet 37. One or more seals 39 can be included to seal the needle 36/fluid conduit 35 interface such that fluid does not travel rearwardly out of the fluid conduit 35, i.e., in the direction opposite the fluid outlet 37. Seal(s) 39 can also assist in maintaining the needle 36 in the center of the fluid conduit 35.

The nozzle portion 30 can further include a reservoir coupler 60 that is configured to sealingly engage the reservoir 14. In some embodiments, the reservoir 14 can include a threaded neck 15 that threadably couples to reservoir coupler 60, for example, by a threaded collar 64. One or more seals 65 can be provided to seal the interface between reservoir coupler 60 and reservoir 14.

Reservoir coupler 60 can include an inlet conduit 61 and a pressurization conduit 62. A removable supply tube 63 can be received within the reservoir 14 and reservoir coupler 60. A first end 63a of the removable supply tube 63 can be arranged at the bottom of the reservoir 14 and a second end 63b can be arranged to sealingly mate with the inlet conduit 61. A fluid filter (not shown) can also be coupled to supply tube 63 to remove foreign objects from the fluid that could damage sprayer 10. The supply tube 63 and inlet conduit 61 can provide a communication path between fluid conduit 35 and the reservoir 14 such that fluid within reservoir 14 can be provided to fluid conduit 35. Pressurization conduit 62 can be arranged to provide pressurized air to reservoir 14 during operation of the sprayer 10 by communicatively coupling reservoir 14 with pressurized air passageway 32. A check valve 66 can be arranged within pressurization conduit 62 to allow pressurized air to enter reservoir 14 while inhibiting fluid within reservoir 14 to enter pressurized air passageway 32.

A trigger assembly 70 can be coupled to the nozzle assembly 33. A user can actuate trigger assembly 70 to begin operation of sprayer 10, as described more fully below. Trigger assembly 70 can include a trigger 71 that is coupled to a trigger collar 72. The trigger collar 72 can be coupled to the needle 36 such that, when the trigger assembly 70 is depressed, the needle 36 will move in an axial direction and open the fluid outlet 37.

A flow adjustment mechanism 73 can be coupled to the trigger assembly 70 to adjust the flow rate of fluid that exits the sprayer 10 during operation. Flow adjustment mechanism 73 can limit movement of the trigger assembly 70 and needle 36 and thereby control the size of the nozzle aperture 37a and flow rate of the sprayer 10. For example, flow adjustment mechanism 73 can act as a mechanical stop for the trigger assembly 70 by contacting the handle portion 20 when the trigger assembly 70 is depressed. As shown in FIG. 2, flow adjustment mechanism 73 can include a rotatable knob that

threadably couples to the trigger assembly 70. A user can adjust the flow rate of the sprayer 10 by rotating the rotatable knob, thereby extending or retracting the flow adjustment mechanism 73. Flow adjustment mechanism 73 can further include a biasing spring that interacts with the knob and assists in maintaining the position of the flow adjustment mechanism 73.

A trigger plunger 80 can be coupled to handle portion 20. Trigger plunger 80 can be coupled with switch 54 and be configured to actuate switch 54 when the trigger assembly 70 is depressed. Trigger plunger 80 can be received within an aperture 81 formed in handle portion 20. A spring 82 or other biasing member can be used to bias the trigger plunger 80 to an extended state whereby switch 54 is turned OFF. Upon depression of the trigger assembly, trigger plunger 80 can contact trigger assembly 70 and be moved to a compressed state whereby switch 54 is turned ON. For example only, switch 54 can be a mechanical switch that includes a lever arm 54a that interacts with trigger plunger 80 (such as switch arm 80d described below).

In various embodiments, sprayer 10 can include a flow rate indicator 280 to provide an indication to the user of the flow rate of sprayer 10. Referring now to FIGS. 9-11, flow rate indicator 280 can include an aperture 281 formed in handle portion 20 and a flow rate projection 282 extending from the main body 80a of trigger plunger 80. Trigger plunger 80 can further include a stop projection 80b, a guide wing 80c and a switch arm 80d. Stop projection 80b can act as a mechanical stop to counter the force of spring 82 and maintain trigger plunger 80 within handle aperture 81. Guide wing 80c can be received within a guide slot 208 formed in handle portion 20. Guide wing 80c and guide slot 208 cooperate to guide movement of the trigger plunger 80. Switch arm 80d can cooperate with lever arm 54a to actuate switch 54. Flow rate projection 282 can be visible through and/or arranged within aperture 281. These markings can be affixed to or formed on handle portion 20 proximate aperture 281. Markings in cooperation with flow rate projection 282 can be utilized to provide an indication to the user of the flow rate of sprayer 10. For example only, the position of flow rate projection 282 in FIG. 10 can indicate no fluid flow, while the position of flow rate projection 282 in FIG. 11 can indicate maximum fluid flow. While flow rate projection 282 moves only in response to trigger assembly 70 being depressed, one skilled in the art can appreciate that flow rate indicator 280 can be constructed to indicate the flow rate with trigger assembly 70 in an undepressed condition.

Sprayer 10 can operate as follows. Reservoir 14 can be filled by first uncoupling the reservoir 14 from the nozzle portion 30 and then pouring a desired fluid through the neck 15 into the reservoir 14. The reservoir 14 can then be sealingly coupled with the nozzle portion 30, e.g., with reservoir coupler 60, such that the first end 63a of supply tube 63 is immersed in the fluid. Power cord 52 can be plugged into a standard household outlet or other source of AC power to provide operating power to the sprayer 10.

A user can then turn ON the sprayer 10, e.g., by depressing trigger assembly 70, which then compresses trigger plunger 80 and actuates switch 54. Actuation of switch 54 can turn ON motor and fan assembly 40 to provide pressurized air to air supply chamber 23. Pressurized air can exit air supply chamber 23 through handle air outlet 25, travel through pressurized air passageway 32 and exit sprayer 10 through the one or more air horn apertures 91. Pressurized air can also be provided to reservoir 14 through pressurization conduit 62 to pressurize the reservoir 14, which can assist with drawing fluid through supply tube 63 into fluid conduit 35 and out of nozzle 34.

during operation. For example only, the pressure inside of reservoir 14 during operation of sprayer 10 can be between 1.5 and 5 pounds per square inch ("psi") or, more specifically, between 2 and 3 psi.

As the trigger assembly 70 is depressed, trigger collar 72 axially moves needle 36 to open fluid outlet 37. In the illustrated example, flow adjustment mechanism 73 acts as a mechanical stop for the trigger assembly 70 and thus limits travel of the needle 36. As described above, the size of the nozzle aperture 37a and the flow rate of the sprayer 10 can vary based on the position of the needle 36 when the trigger assembly 70 is depressed. Fluid will exit the fluid outlet 37 of nozzle 33 and enter the pressurized air stream that is flowing out of air horn aperture(s) 91 to form a fluid spray.

With reference to FIG. 3, a second sprayer constructed in accordance with the teachings of the present disclosure is generally indicated by reference numeral 10'. The sprayer 10' can operate and be constructed identically to sprayer 10, except as described below. Sprayer 10' can include a sprayer body 12' and a reservoir 14 that can be removably coupled to the sprayer body 12'. In the particular example illustrated in FIG. 3, the sprayer 10' is a floor based, high volume low pressure (HVLP) sprayer for spraying fluids, e.g., paints and stains.

Referring now to FIGS. 3 and 4, sprayer body 12' can be coupled to a floor unit 100 by hose 101. In order to reduce the weight and complexity of sprayer body 12', floor unit 100 can include the motor and fan assembly 40 and power supply 50 that is located within handle portion 20 of sprayer 10. A switch 54' can be included on floor unit, e.g., on a handle 102 that can be utilized to move floor unit 100, to selectively power the sprayer 10'. During operation, air can enter the floor unit 100 through apertures in cap 46' and travel through hose 101 to sprayer body 12'. The hose 101 can be coupled to floor unit 100 by coupler 103, which can be a threaded coupler, quick-release coupler or other coupling device.

Sprayer body 12' can include a handle portion 20' coupled to a nozzle portion 30'. Hose 101 can be coupled to the sprayer body 12', e.g., by coupler 120. Similar to coupler 103, coupler 120 can be a threaded coupler, quick-release coupler or other coupling device. Hose 101 can provide pressurized air from floor unit 100 to pressurized air passageway 32 and out through air horn assembly 90, as described above. Further, pressurized air can travel from pressurized air passageway 32 through pressurization conduit 62 and into reservoir 14.

With particular reference to FIGS. 5 and 6, trigger assembly 70' can be coupled to the nozzle assembly 33. A user can actuate trigger assembly 70' to begin operation of sprayer 10'. Trigger assembly 70' can include a trigger 71' that is coupled to a trigger lever 72'. The trigger lever 72' can be coupled to the needle 36 such that, when the trigger assembly 70' is depressed, the needle 36 will move in an axial direction and open the fluid outlet 37. Trigger assembly 70' can further include a biasing member, such as torsion spring 74', that biases the trigger assembly 70' to be in the non-depressed condition and the needle 26 to be in the closed position.

A flow adjustment mechanism 73' can be coupled to the trigger assembly 70' to adjust the flow rate of fluid that exits the sprayer 10' during operation. Flow adjustment mechanism 73' can limit movement of the trigger assembly 70' and needle 36 and thereby control the size of the nozzle aperture 37a and flow rate of the sprayer 10'. For example, flow adjustment mechanism 73' can act as a mechanical stop for the trigger assembly 70' by contacting the trigger lever 72' when the trigger assembly 70' is depressed.

Flow adjustment mechanism 73' can include a rotatable collar 731 that interacts with a coupler 732. For example,

coupler 732 can be threadably coupled to rotatable collar 731 as shown in the Figures. Collar 731 can include a ridge 733 that interacts with sprayer body 12', such as groove 122, to maintain the collar 731 and sprayer body 12' in a specific arrangement and inhibit movement of the collar 731 in the axial direction. Coupler 732 can include a first leg 734 that extends axially from the main body of the coupler 732. First leg 734 can be configured to contact the trigger assembly 70' (such as trigger lever 72') when the trigger assembly 70' is depressed and therefore act as a mechanical stop. Coupler 732 can be slidably coupled to nozzle portion 30' such that, as the collar 731 is rotated, coupler 732 can travel axially, i.e., in the direction of the longitudinal axis of needle 36. In this manner, the position of coupler 732 and first leg 734 can be adjusted to limit movement of the trigger assembly 70' and needle 36, thus controlling the flow rate of sprayer 10'.

Coupler 732 can further include a second leg 735 that includes a flow indicator 736. Second leg 735 can travel axially with the coupler 732 as the collar is rotated. Referring now to FIG. 8, flow indicator 736 may be visible through an aperture or window 140 formed in the handle portion 20' of sprayer 10'. Markings, such as label 141, can be affixed to or formed on handle portion 20'. Flow indicator 736, in cooperation with markings/label 141, can be utilized to provide an indication to the user of the flow rate of sprayer 10'.

With reference to FIGS. 12 and 13 of the drawings, an exemplary reservoir constructed in accordance with the teachings of the present disclosure is generally indicated by reference numeral 300. Reservoir 300 can be utilized, for example, with both sprayer 10 and 10'. Reservoir 300 can include a first threaded neck 315 that threadably couples to reservoir coupler 60, for example, by threaded collar 64. One or more seals 65 can be provided to seal the interface between reservoir coupler 60 and reservoir 300.

Reservoir 300 can be filled by first uncoupling the reservoir 300 from the sprayer body 12, 12' and then pouring a desired liquid through the first threaded neck 315 into the reservoir 300. As will also be appreciated from this disclosure, fluid on reservoir coupler 60, supply tube 63, etc. can drip or spill onto the floor or another object when the reservoir 300 is separated from the reservoir coupler 60 during the filling of the reservoir 300. Such drips and spills can be avoided through use of a second neck 320 on the reservoir 300.

With reference to FIG. 13, the second neck 320 can comprise an annular neck member 321 and a plurality of threads 322 that can be disposed about the annular neck member 321. A cap 350 can be employed to sealingly close the second neck 320 and can comprise a cap body and a seal system 352. The cap 350 can comprise a plurality of threads 353 that can be threadably engaged to the threads 322 of the second neck 320. The seal system 352 can comprise one or more seals that can be employed to sealingly engage the second neck 320 and/or the cap 350 to inhibit the egress of fluids from the reservoir 300.

Second neck 320 can be configured such that cap 350 can be decoupled from reservoir 300 (second neck 320) while the reservoir 300 is coupled to the sprayer body 12, 12'. For example, first threaded neck 315 can be arranged on a first side 300a of reservoir 300 and second neck 320 can be arranged on a second side 300b. As illustrated in FIG. 12, first side 300a can be substantially perpendicular to second side 300b. With this arrangement, it will be appreciated that sprayer 10, 10' need only be tipped on its side and the cap 350 removed to permit access to the interior of the reservoir 300 to fill or empty the reservoir as desired.

The reservoir 300 can be manufactured in various ways, including blow molding or a combination of injection molding and blow molding.

It will be appreciated that the reservoir 300 can be constructed somewhat differently from that which is depicted in FIGS. 12 and 13. For example, the second neck 320 may extend from the body of the reservoir 300 in a direction that is upward and outward so that the reservoir 300 may be filled without tipping the sprayer 10, 10'. Further, the cap 350 can include a threaded body and a lid member that are hingedly coupled. In such a configuration, the reservoir 300 can be filled by rotating the lid member to disengage from the threaded body without decoupling the reservoir 300 from the threaded body. Additionally, the second neck 320 can be formed on a side of the reservoir 300 opposite neck 315 such that the sprayer 10, 10' can be turned upside down to fill the reservoir 300, i.e., first side 300a can be opposite second side 300b.

When filling the reservoir 300 through second neck 320 by turning the sprayer 10, 10' upside down or on its side, it is possible that fluid could enter pressurization conduit 62 and/or pressurized air passageway 32. As described above, a check valve 66 can be arranged within pressurization conduit 62 to inhibit such fluid flow. Check valve 66 can comprise a ball check valve, as is illustrated in FIGS. 2, 4 and 14. Check valve 66 can include a spherical ball 660 arranged in a valve seat body 661. A biasing member, such as compression spring 662, can bias the check valve 66 to the closed position (shown in FIG. 14) in which spherical ball 660 contacts a valve seat defined by valve seat body 661. When pressurized air travels through pressurization conduit 62 in the direction indicated by arrow A, the spherical ball 660 is displaced from the valve seat, which allows pressurized air to enter reservoir 14 or 300. When fluid flows in the direction indicated by arrow B, the spring 662 and fluid act upon spherical ball 660 to contact and seal against the valve seat of valve seat body 661. An adjustment mechanism, such as threaded screw 663, can be included to adjust the force exerted on spherical ball 660 by compression spring 662 to ensure an adequate seal is maintained while also allowing pressurized air flow to travel into the reservoir 14 or 300.

Referring now to FIGS. 15 to 17, an exemplary air horn assembly 90 can include an air horn 92, an air diffuser 93 and a collar 94. As described above, air horn assembly 90 can be coupled to the second end 30b of nozzle portion 30 or 30'. Air diffuser 93 can be partially inserted into pressurized air passageway 32 and be configured to diffuse the pressurized air exiting therefrom. Air horn 92 can be coupled to air diffuser 93. Collar 94 can be coupled to second end 30b, e.g., by threadably coupling to a threaded portion 302, to retain air horn 92 and air diffuser 93 between collar 94 and second end 30b.

Air horn 92 can include one or more air horn projections 95. Air horn projections 95 can be configured to interact with corresponding stop surfaces 96 formed on air diffuser 93. Stop surfaces 96 can act as a mechanical stop to limit rotation of air horn 92. The position of the stop surfaces 96 and air horn projections 95 can correspond to specific positions of air horn assembly 90, such as a vertical spray pattern position or a horizontal spray pattern position. Additionally or alternatively, air horn projections 95 can include one or more protrusions 98 that interact with a corresponding number of notches 97 formed in air diffuser 93. The position of the protrusions 98 and notches 97 can act as a detent mechanism to correspond to specific positions of air horn assembly 90, such as an angled spray pattern position (such as, at an angle of 45 degrees). One skilled in the art will appreciate that the

mechanical stop and/or detent mechanism can be constructed differently from that described above. For example, a notch can be formed in the air horn 92 that interacts with a protrusion on the air diffuser. Furthermore, instead of stop surfaces 96, air horn 92 and air diffuser 93 can include a plurality of detent mechanisms (such as notches 97 and protrusions 98) that correspond to specific positions of air horn assembly 90.

The construction of air horn assembly 90 and nozzle portion 30, 30' can allow for a simple adjustment of the position 10 of the air horn assembly 90. For example, nozzle portion 30, 30' can include ridge member 304 that acts as a mechanical stop for collar 94. A user can arrange the air horn 92 and air diffuser 93 in the desired position and rotate collar 94 until it contacts ridge member 304. Ridge member 304 can be positioned such that the frictional force exerted on air horn 92 when the collar 94 is in contact with ridge member 304 is an amount that inhibits undesired rotation of air horn 92 (such as that caused by vibration during operation of sprayer 10, 10') while allowing a user to rotate the air horn 92 if desired. In this manner, the ridge member 304 and collar 94 can be configured to permit rotation of the air horn 92 without loosening the collar 94 from a fully tightened position (shown in FIG. 17) in which the collar 92 is contact with the ridge member 304. Stop surfaces 96, as well as notches 97 and protrusions 98, can assist in the proper positioning of air horn assembly 90.

The foregoing description of the embodiments has been provided for purposes of illustration and description. It is not intended to be exhaustive or to limit the invention. Individual 30 elements or features of a particular embodiment are generally not limited to that particular embodiment, but, where applicable, are interchangeable and can be used in a selected embodiment, even if not specifically shown or described. The same may also be varied in many ways. Such variations are 35 not to be regarded as a departure from the invention, and all such modifications are intended to be included within the scope of the invention.

What is claimed is:

1. A sprayer for spraying a fluid comprising:
a sprayer body including a handle portion and a nozzle portion, the nozzle portion including a nozzle assembly that defines a fluid outlet, the nozzle assembly including a fluid conduit and a needle arranged within the fluid conduit, the needle being movable to a plurality of positions between a closed position and a fully opened position, the needle closing the fluid outlet in the closed position and fully opening the fluid outlet in the fully opened position;
a fluid reservoir coupled to the sprayer body and in communication with the fluid outlet and fluid conduit;
a trigger assembly coupled to the nozzle assembly and configured to move the needle as the trigger assembly is depressed;
a flow adjustment mechanism coupled to the trigger assembly and configured to adjust a flow rate of the sprayer by limiting movement of the trigger assembly and the needle; and
an air horn assembly including a collar, which is removably coupled to the nozzle portion, an air diffuser that is arranged axially between the collar and the nozzle portion, and a rotatable air horn that is arranged axially between the collar and the nozzle portion, the collar limiting movement of the air horn and the air diffuser away from the nozzle portion but permitting rotation of the air horn relative to the nozzle portion and the collar without loosening the collar from the nozzle portion, wherein the air horn includes at least one air horn pro-

11

jection that limits rotation of the air horn between a first position corresponding to a vertical spray pattern and a second position corresponding to a horizontal spray pattern.

2. The sprayer of claim 1, wherein the air diffuser includes at least one stop surface that interacts with the at least one air horn projection to limit rotation of the air horn. 5

3. A sprayer for spraying a fluid comprising:
a sprayer body including a handle portion and a nozzle portion, the nozzle portion including a nozzle assembly that defines a fluid outlet, the nozzle assembly including a fluid conduit and a needle arranged within the fluid conduit, the needle being movable to a plurality of positions between a closed position and a fully opened position, the needle closing the fluid outlet in the closed position and fully opening the fluid outlet in the fully opened position; 10
a fluid reservoir coupled to the sprayer body and in communication with the fluid outlet and fluid conduit; 20
a trigger assembly coupled to the nozzle assembly and configured to move the needle as the trigger assembly is depressed;
a flow adjustment mechanism coupled to the trigger assembly and configured to adjust a flow rate of the sprayer by limiting movement of the trigger assembly and the needle; and 25
an air horn assembly including a collar, which is removably coupled to the nozzle portion, and a rotatable air horn that is arranged between the collar and the nozzle portion, the air horn assembly configured to permit rotation of the air horn relative to the nozzle portion to a plurality of positions, wherein the air horn includes at least one air horn projection that limits rotation of the air horn between a first position corresponding to a vertical spray pattern and a second position corresponding to a horizontal spray pattern; 30
wherein the air horn assembly further comprises an air diffuser that is arranged between the collar and the nozzle portion, the collar limiting movement of the air diffuser away from the nozzle portion, the air diffuser including at least one stop surface that interacts with the at least one air horn projection to limit rotation of the air horn; and 45

4. The sprayer of claim 3, wherein the detent mechanism comprises a notch defined by the air diffuser and a protrusion on the air horn. 50

5. The sprayer of claim 3, wherein the nozzle portion includes a ridge member that acts as a mechanical stop for the collar. 55

6. The sprayer of claim 5, wherein the ridge member and collar are configured to permit rotation of the air horn without loosening the collar from a fully tightened position in which the collar is in contact with the ridge member.

7. The sprayer of claim 6, wherein the collar is threadably coupled to the nozzle portion. 60

8. The sprayer of claim 2, wherein the nozzle portion includes a ridge member that acts as a mechanical stop for the collar. 65

9. The sprayer of claim 8, wherein the ridge member and collar are configured to permit rotation of the air horn without loosening the collar from a fully tightened position in which the collar is in contact with the ridge member.

12

10. A sprayer for spraying a fluid comprising:
a sprayer body including a handle portion and a nozzle portion, the nozzle portion including a nozzle assembly that defines a fluid outlet, the nozzle assembly including a fluid conduit and a needle arranged within the fluid conduit, the needle being movable to a plurality of positions between a closed position and a fully opened position, the needle closing the fluid outlet in the closed position and fully opening the fluid outlet in the fully opened position;

a fluid reservoir coupled to the sprayer body and in communication with the fluid outlet and fluid conduit; 20
a trigger assembly coupled to the nozzle assembly and configured to move the needle as the trigger assembly is depressed;
a flow adjustment mechanism coupled to the trigger assembly and configured to adjust a flow rate of the sprayer by limiting movement of the trigger assembly and the needle; and

an air horn assembly including a collar, which is threadably coupled to the nozzle portion, an air diffuser that is arranged axially between the collar and the nozzle portion, and a rotatable air horn that is arranged axially between the collar and nozzle portion, the collar limiting movement of the air horn and the air diffuser away from the nozzle portion, wherein the nozzle portion includes a ridge member that acts as a mechanical stop for the collar and wherein the ridge member and collar are configured to permit rotation of the air horn relative to the nozzle portion and the collar without loosening the collar from a fully tightened position in which the collar is in contact with the ridge member. 30

11. The sprayer of claim 10, wherein the air horn and air diffuser include a first detent mechanism that inhibits rotation of the air horn from a first position.

12. The sprayer of claim 11, wherein the first detent mechanism comprises a notch defined by the air diffuser and a protrusion on the air horn. 40

13. A sprayer for spraying a fluid comprising:
a sprayer body including a handle portion and a nozzle portion, the nozzle portion including a nozzle assembly that defines a fluid outlet, the nozzle assembly including a fluid conduit and a needle arranged within the fluid conduit, the needle being movable to a plurality of positions between a closed position and a fully opened position, the needle closing the fluid outlet in the closed position and fully opening the fluid outlet in the fully opened position;

a fluid reservoir coupled to the sprayer body and in communication with the fluid outlet and fluid conduit; 20
a trigger assembly coupled to the nozzle assembly and configured to move the needle as the trigger assembly is depressed;
a flow adjustment mechanism coupled to the trigger assembly and configured to adjust a flow rate of the sprayer by limiting movement of the trigger assembly and the needle; and

an air horn assembly including a collar, which is removably coupled to the nozzle portion, and a rotatable air horn that is arranged between the collar and nozzle portion, the air horn assembly configured to permit rotation of the air horn to a plurality of positions, wherein the nozzle portion includes a ridge member that acts as a mechanical stop for the collar and wherein the ridge member and collar are configured to permit rotation of the air horn 30

13

without loosening the collar from a fully tightened position in which the collar is in contact with the ridge member;

wherein the air horn assembly further comprises an air diffuser that is arranged between the collar and the nozzle portion, the collar limiting movement of the air diffuser away from the nozzle portion, the air horn and air diffuser including a first detent mechanism that inhibits rotation of the air horn from a first position; and wherein the air horn and air diffuser include a second detent mechanism that inhibits rotation of the air horn from a second position and a third detent mechanism that inhibits rotation of the air horn from a third position.

14. The sprayer of claim 13, wherein the first position corresponds to a vertical spray pattern, the second position corresponds to a horizontal spray pattern and the third position corresponds to an angled spray pattern.

15. The sprayer of claim 14, wherein the angled spray pattern corresponds to an angle of 45 degrees.

16. The sprayer of claim 15, wherein the collar is threadably coupled to the nozzle portion.

17. The sprayer of claim 13, wherein each of the first, second and third detent mechanisms comprises a notch defined by the air diffuser and a protrusion on the air horn.

18. A sprayer for spraying a fluid comprising:

a sprayer body including a handle portion and a nozzle portion, the nozzle portion including a nozzle assembly that defines a fluid outlet, the nozzle assembly including a fluid conduit and a needle arranged within the fluid conduit, the needle being movable to a plurality of positions between a closed position and a fully opened position, the needle closing the fluid outlet in the closed position and fully opening the fluid outlet in the fully opened position;

a fluid reservoir coupled to the sprayer body and in communication with the fluid outlet and fluid conduit;

a trigger assembly coupled to the nozzle assembly and configured to move the needle as the trigger assembly is depressed;

a flow adjustment mechanism coupled to the trigger assembly and configured to adjust a flow rate of the sprayer; and

an air horn assembly including a collar removably coupled to the nozzle portion, an air diffuser that is arranged axially between the collar and the nozzle portion, the collar limiting movement of the air diffuser away from the nozzle portion, and a rotatable air horn arranged axially between the collar and air diffuser, the air horn assembly configured to permit rotation of the air horn relative to the nozzle portion and the collar to a plurality of positions, wherein:

14

- (i) the nozzle portion includes a ridge member that acts as a mechanical stop for the collar,
- (ii) the ridge member and collar are configured to permit rotation of the air horn without loosening the collar from a fully tightened position in which the collar is in contact with the ridge member,
- (iii) the air horn includes at least one air horn projection, and
- (iv) the air diffuser includes at least one stop surface that interacts with the at least one air horn projection to limit rotation of the air horn between a first position corresponding to a vertical spray pattern and a second position corresponding to a horizontal spray pattern.

19. The sprayer of claim 18, wherein the air horn and air diffuser include a detent mechanism that inhibits rotation of the air horn from a third position.

20. The sprayer of claim 18, wherein the collar is threadably coupled to the nozzle portion.

21. The sprayer of claim 2, wherein the air horn and the air diffuser include a detent mechanism that inhibits rotation of the air horn from a third position.

22. The sprayer of claim 21, wherein the detent mechanism comprises a notch defined by the air diffuser and a protrusion on the air horn.

23. The sprayer of claim 21, wherein the nozzle portion includes a ridge member that acts as a mechanical stop for the collar.

24. The sprayer of claim 23, wherein the ridge member and collar are configured to permit rotation of the air horn without loosening the collar from a fully tightened position in which the collar is in contact with the ridge member.

25. The sprayer of claim 24, wherein the collar is threadably coupled to the nozzle portion.

26. The sprayer of claim 11, wherein the air horn and air diffuser include a second detent mechanism that inhibits rotation of the air horn from a second position and a third detent mechanism that inhibits rotation of the air horn from a third position.

27. The sprayer of claim 26, wherein the first position corresponds to a vertical spray pattern, the second position corresponds to a horizontal spray pattern and the third position corresponds to an angled spray pattern.

28. The sprayer of claim 27, wherein the angled spray pattern corresponds to an angle of 45 degrees.

29. The sprayer of claim 28, wherein the collar is threadably coupled to the nozzle portion.

30. The sprayer of claim 26, wherein each of the first, second and third detent mechanisms comprises a notch defined by the air diffuser and a protrusion on the air horn.
